SLEEVE MOUNTING MEANS

James Christensen, Lancaster, Pa., assignor to Schick Electric Inc., a corporation of Delaware
Filed Dec. 26, 1962, Ser. No. 247,073
3 Claims. (Cl. 29—117)

The invention is concerned generally with hollow, cylindrical devices as used for painting, polishing, sanding and so forth. Some of such devices are designed to be power driven and others—as in the case of paint rollers—to be manually manipulated; but they have in common the need of a suitable mandrel-like supporting member inserted at one end and by or with which they are rotated.

The object of the invention is to provide a simple, inexpensive construction of cooperating roller or driven member and mounting means so organized as to enable them to be readily assembled and disassembled and, when assembled, to ensure against slippage—that is, relative rotary motion—of the one with respect to the other.

For purposes of illustration, the invention is shown and will be described with reference to the mounting of the "brush" or polishing element of an electric shoe polisher. Generically, the brush will be referred to as the sleeve member and the driving member inserted into it as the mounting member.

The invention will be readily understood from the following description of the accompanying drawings of a preferred form, in which:

FIG. 1 is a partially broken out and sectioned side elevational view of a shoe polisher roller and its mounting member according to the invention;

FIG. 2 is a perspective view of the mounting member of FIG. 1;

FIG. 3 is a top plan view of the mounting member; and

FIGS. 4 and 5 are elevational views, respectively, of the left and right hand ends of the mounting member.

In general, the invention contemplates a sleeve member having a hollow, semi-rigid, cylindrical core and a mounting member for insertion into one end of the core, the mounting member, of one-piece construction for press-fitting by hand into the core, at its leading end being of circular cross section dimensioned to enter and closely fit the core and, from adjacent its leading end toward its trailing end, having a gradually increasing maximum diameter and being out of round, whereby to deform the core at and adjacent its entered end to substantially elliptical shape.

In FIG. 1, the sleeve member, generally designated 10, is shown as consisting of a core 11 having its entire cylindrical outer surface coated or covered with textile or other suitable polishing material 12. The core is made of any suitable material—paper board, plastic or the like—and is semi-rigid in the sense that while stiff, it will yield or deform when the mounting member is forced into it under normal hand pressure.

As viewed in FIGS. 1 and 2, the profile of the mounting member, generally designated 15, is seen to be more or less wedge shaped, with a uniform taper throughout its length. Its leading or entering end 16, as stated, is circular and provides a close fit with the core 11 of the driven member 16.

Throughout its length, which is substantially less than that of the driven member, the mounting member is formed with smooth, continuous upper and lower arcuate surfaces 17, 18, which are relatively short in the circumferential direction but nevertheless extend a sufficient distance on each side of the top and bottom cen-

2

ter as to have no tendency to cause the core of the sleeve member to crease or take abrupt or angular bends as it is deformed. The flanges 19, 20, of course, serve to limit the entry of the mounting member into the sleeve member.

The arcuate surfaces 17, 18, diverge slightly as they recede from the leading end, providing the gradually increasing maximum diameter mentioned above and, of course, exceeding the normal diameter of the core 11. Not only do these surfaces diverge toward the trailing end but they also become what is referred to above as out of round. By that is meant that they cease to be parts of a circle concentric with the circular leading end of the mounting member. In other words, as shown in FIG. 5, they become the major axis arcuate ends of an elliptical form; that is, the arcs at the ends of the major diameter of a generally elliptical shape. Accordingly, the insertion of the mounting member into the sleeve member deforms the latter to the substantially elliptical shape indicated by the broken outline 22 in FIG. 4. This, it is found, results in an extremely effective non-slipping drive connection between the two members. Because of its deformation to elliptical form, the core, in effect, is "keyed" to the mounting member, so that relative rotation between the two members is resisted not by friction alone (as would be the case if the mounting member were merely tapered and of circular section throughout) but by friction plus the resistance of the core of the sleeve member to the continual deforming and reforming which relative rotation between the members would entail. In the result, the two members can be much more readily engaged and disengaged, by end-wise relative movement, than if an equal driving torque were obtained by friction alone.

In the preferred form illustrated, the sides of the out of round portion of the mounting member, intermediate the arcuate surfaces, consist of parallel flats 23, 24.

As will be recognized, the mounting member is appropriately designed for convenient moulding of suitable plastic and is cup shaped or tubular throughout the major portion of its length, the base 25 of the cup supporting an internal hub 26 to receive a shaft (not shown) to which the mounting member may be secured in any appropriate way.

In order to accommodate the mounting member to reasonable tolerances for the internal diameter of the core of the sleeve member, provision may be made for imparting a degree of yieldability to the arcuate portions of the mounting member, especially in the region of maximum diameter. As shown, the longitudinal or lower edge 30 of flat 23 is separated and spaced from arcuate portion 18 by a slit 31; and, similarly, the diametrically opposite or upper edge 32 of flat 24 is spaced from arcuate portion 19 by a slit 33. Thus the slits will permit a slight bodily yield of the adjacent larger diameter areas if the insertion of the mounting member into the deformed core encounters abnormal resistance, due to the core being somewhat undersize.

It will be seen and understood, of course, that the major axis diameter of the mounting member at its trailing end is of greater length than the normal (that is, prior to assembly) internal diameter of the deformable core and that, to accommodate the resulting elliptical deformation of the core, the minor axis diameter of the trailing end of the mounting member (whether or not the sides are flattened) is necessarily less than the normal internal diameter of the core. However, it is found that the amount of deformation of the core required to effect a secure attachment of the sleeve member to the mounting member is not such as to impair or interfere with the action of the outer or applicator surface of the sleeve member in use.

The following is claimed:

1. The combination of a sleeve member having a hollow, semi-rigid cylindrical core and a mounting member disposed within one end of the core, the mounting member at its leading end being of circular cross section dimensioned to closely fit the core, and from adjacent its leading end toward its trailing end having successive cross sections comprising oppositely disposed, relatively short arcuate portions of gradually increasing distance from one another, with intervening parallel flats, the portion of the mounting member incorporating the flats being tubular and open at its trailing end; one longitudinal edge of one flat being spaced from one of the arcuate portions and one longitudinal edge of the other flat being spaced from the other arcuate portion.

2. The combination of a sleeve member having a hollow, semi-rigid, normally cylindrical core and means deforming one end of the core to elliptical cross sectional form comprising a one-piece mounting member disposed in said one end of the core, the mounting member at its leading end being of circular cross section dimensioned to fit the core and from that end toward its trailing end being of generally elliptical cross sectional form incorporating diametrically opposite curved surfaces comprising the major axis arcuate ends of the elliptical form, the length of said major axis at the trailing end of the mounting member being greater than the normal internal diameter of the core and the length of the minor axis of the mounting member at its trailing end being less than the normal internal diameter of the core and the mounting member in the central longitudinal sec-

tion through said major axis presenting a uniform taper from its trailing end to its leading end, the mounting also being tubular throughout the major portion of its length and its walls intermediate the said major axis arcuate surfaces incorporating longitudinal slits which are open-ended at the trailing end of the mounting member, for the purpose described.

3. The combination of a sleeve member having a hollow, semi-rigid, normally cylindrical core and means deforming one end of the core to elliptical cross sectional form comprising a one-piece mounting member disposed in said one end of the core, the mounting member at its leading end being of circular cross section dimensioned to fit the core and from that end toward and at its trailing end being of generally elliptical cross sectional form incorporating diametrically opposite curved surfaces comprising the major axis arcuate ends of the elliptical form, the length of said major axis at the trailing end of the mounting member being greater than the normal internal diameter of the core and the length of the minor axis of the mounting member at its trailing end being less than the normal internal diameter of the core and the mounting member in the central longitudinal section through said major axis presenting a uniform taper from its trailing end to its leading end.
